UNITED STATES PATENT OFFICE.

GEORGE H. GILLIGAN, OF NEW BEDFORD, MASSACHUSETTS, ASSIGNOR TO U. S. RING TRAVELER COMPANY, A CORPORATION OF RHODE ISLAND.

RING TRAVELER.

Application filed December 1, 1922. Serial No. 604,408.

To all whom it may concern:

Be it known that I, GEORGE H. GILLIGAN, a citizen of the United States, residing at New Bedford, in the county of Bristol and

5 State of Massachusetts, have invented certain new and useful Improvements in Ring Travelers, of which the following is a specification.

My invention relates to ring travelers for 10 use upon horizontal or flanged rings in distinction from vertical or unflanged rings.

An essential object of my invention is to avoid the excessive friction or cramping of the traveler in its course around the ring 15 occasioned by passing the thread beneath the traveler, whereby the latter is tilted bringing its bow and horns into contact with the ring. The friction or cramping develops heat not only in the ring, but draws the 20 temper of the traveler itself, softening the latter to such an extent as to be easily worn and destroyed, thus occasioning waste, stoppage and expense.

A further object is to facilitate initial 25 engagement of the thread with the traveler.

Other objects and advantages of the invention will be apparent as it is better understood from the following description when considered in connection with the accompanying drawings illustrating a preferred embodiment thereof and constituting a part of this specification.

In the drawings Figure 1 is a perspective view of a ring showing my traveler engaged 35 therewith; Figure 2, a fragmentary front elevation of the ring on which the traveler is shown mounted; Figure 3, a section on line 3—3 of Figure 2, and Figure 4, a perspective view of the traveler.

40 Like reference numerals indicate corresponding parts throughout the views.

In the drawings 6 is the web, and 7 the operating flange of a ring of a usual spinning or twisting frame in conjunction with my novel traveler is illustrated.

45 The traveler consists of the usual bow 8 and end lips 9.

Cut and bent up from the material of the bow centrally and longitudinally thereof is a narrow arched finger 11 extending above the bow with its integral extremity near one end of the bow. Its free extremity 13 is sufficiently spaced from the bow to permit the thread 15, extending from the rolls to the bobbin, to be passed thereunder from the front to enter the bight portion 16 of the finger.

50 It will be observed that the location of the thread below the finger 11 rather than below the bow 8 balances the traveler and prevents any canting of the bow in the direction of travel of the latter, thus avoiding cramping, heating, or wear; and insertion of the thread under the finger enables instantaneous threading of the traveler; that the thread is 55 remote from the oily surface of the ring; and that the traveler is inexpensive to construct.

56 I claim:—

1. In a ring traveler, a bow, terminal 70 horns on the bow, and a finger upon the bow elevated therefrom to admit a thread to pass between the finger and the bow.

2. In a ring traveler, a bow, terminal 75 horns upon the bow, and a finger fast to the bow near one end thereof, and disposed longitudinally thereof with its free end spaced from the bow.

In testimony whereof I have affixed my signature.

GEORGE H. GILLIGAN.
